(Continued)

Primary Examiner — John Windmuller(74) *Attorney, Agent, or Firm* — Fogg & Powers LLC(57) **CLAIM**

The ornamental design for an transceiver, as shown and described.

DESCRIPTION

FIG. 1 is a perspective view of an antenna case.

FIG. 2 is another perspective view of the antenna case of FIG. 1.

FIG. 3 is a front view of the antenna case of FIG. 1.

FIG. 4 is a right side view of the antenna case of FIG. 1, the left side view being a mirror image of the right side view; and,

FIG. 5 is a top view of the antenna case of FIG. 1, a bottom view being a mirror image of the top view.

1 Claim, 4 Drawing Sheets(56)
